UNITED STATES PATENT OFFICE.

SAMUEL S. LINN, OF ALTA LOMA, TEXAS.

MEDICAL PREPARATION.

1,284,117.

Specification of Letters Patent. Patented Nov. 5, 1918.

No Drawing.

Application filed September 18, 1918. Serial No. 254,323.

To all whom it may concern:

Be it known that I, SAMUEL S. LINN, a citizen of the United States, residing at Alta Loma, in the county of Galveston and State of Texas, have invented certain new and useful Improvements in Medical Preparations, of which the following is a specification.

This invention relates to medical preparations and more particularly for use in afflictions of the human body known as eczema and kindred diseases.

The object of this invention is to provide a simple and inexpensive lotion for use in the treatment of eczema and kindred diseases, and the following is the formula for the proper manufacture of the medical preparations:

The lotion comprises a body of crude petroleum, preferably that obtained from southern oil fields, and commonly known as Beaumont oil. To one gallon of such oil add one ounce of oil of wintergreen and one

ounce of essence of peppermint, and thoroughly mix the same. These proportions, however, may be slightly varied to secure a slight predominance of either oil of wintergreen, or of the essence of peppermint. In its application the compound is applied locally to the affected parts, and is of especial merit in the treatment of cases of eczema and similar affections of the skin.

Having thus described my invention I claim—

1. A lotion compound comprising substantially one hundred parts of crude oil of petroleum and one part each of oil of wintergreen and essence of peppermint, substantially as described.

2. To one gallon of Beaumont crude oil add one ounce of oil of wintergreen and one ounce of essence of peppermint.

In testimony whereof I affix my signature to this specification on the 9 day of September, A. D., 1918.

SAMUEL S. LINN.
